UNITED STATES PATENT OFFICE.

ABRAHAM L. HOLTZMAN, OF EAST ORANGE, NEW JERSEY.

TOOTH-BRUSH.

1,045,552.

Specification of Letters Patent.

Patented Nov. 26, 1912.

Application filed June 10, 1912. Serial No. 702,758.

To all whom it may concern:

Be it known that I, ABRAHAM L. HOLTZMAN, a citizen of the United States, and a resident of East Orange, in the county of 5 Essex and State of New Jersey, have invented a new and Improved Tooth-Brush, of which the following is a full, clear, and exact description.

The object of the invention is to provide 10 a new and improved tooth-brush provided with a removable bristle holder to permit of replacing the same when the bristles are worn out and thus allow the use of a single expensive brush handle with a number of 15 bristle holders for a long period.

For the purpose mentioned, use is made 20 of a handle having a seat for the reception of a bristle holder, and means for removably securing the said bristle holder on the said 25 seat.

A practical embodiment of the invention is represented in the accompanying drawings forming a part of this specification, in 30 which similar characters of reference indicate corresponding parts in all the views.

Figure 1 is a perspective view of the 35 tooth-brush; Fig. 2 is a longitudinal section of the same. Fig. 3 is a cross section of the same and showing more particularly the insertion of a bristle holder onto its seat; Fig. 4 is a perspective view of the cover and locking plate; Fig. 5 is a similar view of the bristle holder; and Fig. 6 is a perspective view of a paper carrier for 40 temporary use when placing a bristle holder in position on the brush.

The handle A of the tooth-brush is provided at its forward end with an integral loop B having at its inner wall an annular 45 seat or rabbet C on which is adapted to be seated the back D of a bristle holder having bristles E set in the usual manner in the back D. The outer end of the loop B is provided with an overhang F under which fits the forward end of a covering and locking plate G fitting into the opening of the loop B at the top thereof, as plainly indicated in Figs. 1 and 2. The rear end of the covering and locking plate G is provided 50 with a rearwardly-extending tongue G' fitting into a recess A' formed in the top of the handle A adjacent the loop B, and the tongue G' is adapted to be engaged by a

ring H slidably held on the handle A to clamp the tongue G' in position in the recess A'. In order to hold the ring H against accidental displacement on the tongue G' the latter is provided at the top with a recess G² into which the upper portion of the ring H fits. By reference to Fig. 2, it will 55 be seen that the covering and locking plate G overlies the back D of the bristle holder, and as the said plate G is held in position at its forward end by the overhang F and at its rear end by the ring H it is evident 60 that the bristle holder is securely held in position on its seat C to permit the use of 65 the tooth-brush for cleaning purposes in the usual manner.

In case the bristles E are worn out, the 70 operator slips the ring H rearwardly on the handle A out of engagement with the tongue G' to permit lifting the covering plate G out of the loop B, thus unlocking 75 the bristle holder, which can now be pushed out of the loop B and replaced by a new bristle holder. When this has been done the covering plate G is replaced in the loop B and locked in position, as above explained. In order to permit convenient insertion of 80 the bristle holder into the loop B, use is preferably made of a V-shaped piece of paper I, into which the bristles E are passed, as indicated in Fig. 3, and the bristle holder with the piece of paper I is then slipped 85 into the opening of the loop B to seat the back D on the seat or rabbet C.

By the arrangement described, the bristles E are not liable to come in contact with the seat of the rabbet C and consequently 90 the bristle holder can be conveniently and easily inserted in the loop B.

It is understood that after the back D is seated on the seat or rabbet C the piece of paper I is thrown away.

Having thus described my invention, I claim as new and desire to secure by Letters Patent:

A brush, comprising a handle having an integral loop provided with an annular seat 100 and with an overhang at the outer end, a bristle holder having a back carrying bristles and seated on the said seat, a covering and locking plate fitting into the opening of the said loop and overlying the said 105 back and which is entirely separable from

the loop and bristle holder, the outer end of the plate extending under the said overhang and the inner end of the said plate terminating in a tongue, and a ring slideable on the handle and adapted to engage the said tongue and clamp the same against the handle.

In testimony whereof I have signed my name to this specification in the presence of two subscribing witnesses.

ABRAHAM L. HOLTZMAN.
